UNITED STATES PATENT OFFICE.

FREDRICK O. COLLAR, OF ASHTABULA, AND HERBERT E. WETHERBEE, OF CLEVELAND, OHIO, ASSIGNORS OF ONE-HALF TO BENEDICT CROWELL AND CHARLES B. MURRAY, DOING BUSINESS UNDER THE FIRM-NAME OF CROWELL & MURRAY, OF CLEVELAND, OHIO.

APPARATUS FOR SAMPLING ORES.

1,192,990.

Specification of Letters Patent.

Patented Aug. 1, 1916.

Application filed October 30, 1915. Serial No. 58,936.

To all whom it may concern:

Be it known that we, FREDRICK O. COLLAR, of Ashtabula, in the county of Ashtabula and State of Ohio, and HERBERT E. WETHERBEE, of Cleveland, in the county of Cuyahoga and State of Ohio, both citizens of the United States, have invented certain new and useful Improvements in Apparatus for Sampling Ores; and we do hereby declare the following to be a full, clear, and exact description of the invention, such as will enable others skilled in the art to which it appertains to make and use the same.

Our invention relates to an improvement in apparatus for sampling ores.

The usual custom is to sell Lake Superior iron ore on a guarantee to be of a certain quality, and if the analysis shows it to be better than the guarantee a premium is paid, and if of a lower grade a penalty is enforced. The sampling is done by disinterested parties acting as umpires between the buyer and seller, and each cargo of ore is considered as a unit and every effort is made to get a fair average sample of each cargo as it is unloaded. In taking the samples equal volumes of lump and fine ore are taken at regular measured intervals as fresh surfaces are exposed, and after a sufficient quantity has accumulated it is crushed, mixed and quartered, and a part preserved for testing purposes.

In recent years the size of the boats engaged in the ore trade and the speed of unloading have greatly increased, so that now considerably more ore is handled in much less time than formerly, consequently the difficulties in obtaining a fair average sample of the cargo have greatly increased. This has been offset by increasing the number of men engaged in sampling, but it is generally admitted that under the present conditions of unloading a mechanical sample would be desirable.

The object of our invention is to provide means for automatically securing a sample from each bucket of ore taken from the boat, and it consists in a container carried by one jaw of the bucket and a plunger carried by the other jaw for forcing a small quantity

of the ore into the container each time the jaws of the bucket are closed.

It further consists in the parts and combinations of parts as will be more fully explained and pointed out in the claims.

In the accompanying drawings, Figure 1 is a diagrammatic view in side elevation of the bucket of an unloading machine, also showing in dotted lines, the position of the jaws of the bucket when the latter is open. Figs. 2 and 3 are views in elevation of the container and its supporting die and block. Figs. 4 and 5 are views in elevation of the plunger. Figs. 6 and 7 are enlarged views of the die through which the ore is forced into the container showing in dotted lines the shape of the bore in the die. Fig. 8 is an end view of the block which supports the rear end of the container, and Figs. 9 and 10 are views of the container.

1 and 2 represent the two jaws or members of an unloading bucket which when closed and filled are in the position shown in full lines in Fig. 1, and which when open approximate the position shown in dotted lines.

Secured to the jaw 1, at the edge thereof, is the die block 3, and secured to the jaw 2 is the plunger 4, the latter being so located as to enter the bore in the die each time the jaws of the bucket are moved into closed position. The die 3 consists of a metal block, preferably manganese steel, having side flanges 5 for the passage of the screws, rivets or other devices which secure it to the inner face of the side of the bucket section or jaw, and provided with a central bore the two ends of which are tapered as shown in dotted lines at 6 and 7 Fig. 7, while the intermediate section 8 of the bore is cylindrical and of less diameter than the outer end of the tapering section 6, so that the ore, as it is forced into the die, will become wedged and packed in the smaller cylindrical section of the die and not fall out during the opening and closing movements of the jaws.

The rear tapering end 7 of the bore is to receive and support the front end of the container 9, the rear end of the latter being

detachably supported by the block 10 secured to the inner face of the bucket by screws, rivets or other fastening devices. This block has a central projection 11 forming an abutment for the rear end of the container, and is also provided with the curved clamp 12, hinged to the block and adapted to take over the rear end of the container when the latter is properly seated on the block 10, the clamp being locked in place by the pin 13. From the foregoing it will be seen that when the rear end of the container 9 is released from the block 10 it can be readily and quickly connected to and disconnected from the die, the tapering end 7 of the bore permitting of the freedom of movement necessary to the attachment and release of the container and also operating to properly center the container with relation to the die. It will also be seen that the container can be quickly removed and replaced by another so that there will be but little if any interference with the normal working of the unloading apparatus.

25 The plunger 4 is secured to the jaw 2 in alinement with the bore of the die so that as the jaws approach each other in closing, the plunger will enter the die and force the ore, which will have filled the bore of the die during the movement of the jaws toward each other, into the intermediate restricted position 8 of the bore and into the container at the rear of the die.

185 The container 9 is preferably slotted as shown in Fig. 9 to facilitate the removal of the ore from the container. The ore packs in the latter and by slotting the container it is rendered more flexible so that when tapped with a hammer or other tool 190 the ore will be more readily dislodged. If desired the container may be made of two sections hinged together as shown in Fig. 10, which construction is better adapted for handling wet or sticky ore.

48 The hinged clamp 12, for locking the rear end of the container to the block 10, is provided at its pivoted end with a shoulder or stop 14, which, when the clamp is turned outwardly to release the container, 50 abuts against the block and holds the clamp 12 approximately horizontal and in a position to prevent the container from accidentally sliding off the block during the operation of removing the latter from the 55 bucket.

With the bucket provided with the attachment described, it will be seen that each time the bucket is filled, an equal amount of ore will be caught and forced into the die 60 and from the latter into the container, and each container is of sufficient length so that the bucket can be filled a number of times before the container becomes filled. The filled or partly filled container may be removed and an empty one inserted when the 65

machine is stopped for oiling so as not to delay or interfere with the operation of unloading.

We prefer to use a container and its dies and plungers at each side of the bucket so as to secure two samples from each bucket full of ore unloaded.

With our improvement an equal amount of ore is taken each time the bucket is filled during the various stages of unloading from the start to the finish, thus dispensing altogether with the necessity of going into the hold and eliminating entirely the possibility of injury by the unloading machine or by falling ore.

While we have described our invention in certain preferred embodiments, modifications might be made without departing from the invention. Therefore we do not wish to be understood as limiting the invention to the particular arrangements, constructions and devices shown and described except so far as certain of the claims herein are limited thereto by their express language.

Having fully described our invention what we claim as new and desire to secure by Letters-Patent, is:

1. In an apparatus for sampling ore, the combination of a bucket composed of a plurality of jaws, a container carried by one jaw and a plunger carried by another jaw and adapted to force ore into the container each time the jaws of the bucket are closed.
2. In an apparatus for sampling ore, the combination of a bucket composed of two jaws, a container detachably carried by one jaw and plunger carried by the other jaw and adapted to force ore into the container each time the bucket is filled.
3. In an apparatus for sampling ore, the combination of a bucket having two jaws, a die secured to one jaw, a plunger secured to the other jaw and adapted to enter the die each time the bucket is filled, and a container connected with the die so as to receive the ore forced into the latter by the plunger.
4. In an apparatus for sampling ore, the combination of a bucket having two jaws, a die secured to one jaw, a plunger secured to the other jaw and a container removably secured to the die and forming a continuation thereof.
5. In an apparatus for sampling ore, the combination of a bucket having two jaws, a die secured to one jaw, a plunger secured to the other jaw and adapted to enter the die each time the bucket is filled, and a tubular container supported at one end by the die and detachably secured at its other end to a support.

6. In an apparatus for sampling ore, the combination of a bucket having two jaws, a die secured to one jaw, the said die having a tapering bore whereby the ore will be com-

- 5 pacted during its passage through the die, a
container to receive the ore forced through
the die and a plunger carried by the other
jaw of the bucket and adapted to enter the
5 die each time the bucket is filled.
- 10 7. In an apparatus for sampling ores, the
combination of a bucket having two jaws, a
die secured to one jaw, a block secured to
said jaw in rear of the die, a movable con-
tainer mounted at its front end in the die
and detachably secured at its rear end to the
block, and a plunger secured to the other
jaw of the bucket and adapted to enter the
die each time the bucket is filled.
- 15 8. An attachment for ore unloading ma-
chines consisting of a plunger, a die coaxing
with the plunger and a removable container
communicating with the bore of the die and

adapted to receive the ore forced through
the die by the plunger.

9. An attachment for ore unloading ma-
chines, consisting of a plunger, a die having
a bore flaring outwardly at its front end, a
removable container communicating with
the bore of the die at the rear end of the lat-
ter for receiving the ore forced through the
die by the plunger.

20 25 In testimony whereof, we have signed this
specification in the presence of two subscrib-
ing witnesses.
